UNITED STATES PATENT OFFICE.

JOSEPH L. SCHWARTZ, OF PHILADELPHIA, PENNSYLVANIA.

SALES-STIMULATOR BOOK.

Application filed November 28, 1923. Serial No. 677,374.

To all whom it may concern:

Be it known that I, JOSEPH L. SCHWARTZ, a citizen of the United States, residing at Philadelphia, in the county of Philadelphia, 5 State of Pennsylvania, have invented a new and useful Sales-Stimulator Book, of which the following is a specification.

This invention, generally stated, relates to books as used by fraternal, charitable, 10 religious, and other organizations in securing funds for the up-keep and maintenance thereof.

The leading objects of the present invention are to provide a book of this character, 15 calculated to stimulate sales by increasing interest in the project because of the novelty of the plan pursued; calculated to remove all possibility of the winning or prize symbol being discovered prior to complete sale of 20 the book; and further calculated to preclude the possibility of a purchaser knowing in advance the sales price of a ticket to be withdrawn from the book.

A further object of the present invention 25 relates to the providing of a novel arrangement and combination of book-parts for attaining the results sought by said leading objects.

Other and further objects not at this time 30 pointed out will appear hereinafter.

The invention consists of the novel construction hereinafter described and finally claimed.

The nature, characteristic features and 35 scope of the invention will be more fully understood from the following description taken in connection with the accompanying drawings forming part hereof, and in which:

40 Fig. 1, is a perspective view of a sales stimulator book embodying features of the invention.

45 Fig. 2, is a similar view of a ticket and complementary stub part as removed from the book shown in Fig. 1.

Fig. 3, is a top or plan view of the book shown in Fig. 1, with the sealing means broken and the cover folded back to show ticket and stub construction.

50 Fig. 4, is a view in cross section taken upon the line 4—4 of Fig. 1.

Fig. 5, is a fragmentary view in plan illustrating the uppermost ticket shown in Fig. 3, and

Fig. 6, is a similar view of a ticket located 55 immediately below the ticket shown in Fig. 3.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously 60 arranged and organized and that my invention is not limited to the precise arrangement and organization of the instrumentalities as herein shown and described.

Referring now to the drawings in detail, 70 the numeral 1, designates a plurality of stub parts which together with a back 2, and a cover 3, are securely held together as by means of a staple 4. Secured to each stub part 1, for detachable removal along a 75 weakened line 5, is a second stub part 6 having formed integral therewith a ticket 7

which in practice is usually an admission ticket to some function. The stub parts 1, and 6, in manufacture are severed along a 80 diagonal line, as at 8, the line of severing of alternate tickets being in opposed relation, as clearly shown in Fig. 3, the purpose of which will presently appear. Each stub 6, is provided with a ticket sales price as 85 indicated at 9. This sales price is arranged, preferably, immediately adjacent the weakened line 5. It is thus apparent that the sales price of the various stubs 6 are disposed in staggered relation with one another. 90

The purpose of this is to conceal from view the sales price of each ticket prior to the time that such ticket is removed from a book. This is so, because the stub part 1, of one ticket is always over the stub part 6, 95 of a ticket immediately therebelow. Each ticket 7, has printed thereon, as at 10, possible prize indicia which may be a number, name or the like. For the sake of illustration, feminine names have been used in the 100 drawings. In addition to such prize indicia the ticket has printed thereon data denoting the purpose for which the ticket is sold, and which obviously varies according to the use for which it is to be put. The cover 3, has 105 delineated thereon winning prize indicia as indicated by dotted lines in Figs. 1 and 3, and denoted by the numeral 11. This prize

indicia is arranged upon that part of the cover 3 immediately above the stub parts 1 and 6. A seal 12, preferably a ribbon or strip of red paper, is placed over the prize 5 indicia 11, and a band 13, secured around the cover, backing and stub parts, as clearly indicated in Figs. 1 and 4. The band 13, thus arranged completely conceals from view the stub parts so that when the flexible 10 cover 3 is folded back along the edge 14, of the band 13, the face only of ticket 7, is discernible. To remove a ticket the purchaser pulls firmly upon the outer end thereof so as to detach same along the weakened 15 line 5. With the ticket removed from the book the purchase price is determined. After all tickets have been sold the band 13, is cut or broken away so that seal 12, may be removed, whereupon the prize winning 20 indicia 11, is clearly discernible. The holder of the ticket having corresponding indicia thereon is the winner of a prize. As an added inducement each book may be provided with a number upon its cover as at 25 15, and the purchaser pulling a ticket bearing this number as a sales price receives an additional prize.

It will now be apparent that I have devised a novel and useful construction which 30 embodies the features of advantage enumerated as desirable in the statement of the invention and the above description and while I have in the present instance shown and described the preferred embodiment thereof 35 which has been found in practice to give satisfactory and reliable results, it is to be understood that the same is susceptible of modification in various particulars without departing from the spirit or scope of the invention or sacrificing any of its advantages.

The herein described device is not to be confused with lottery or like games of chance because the purchaser of a ticket obtains value received in that said ticket is a 40 means of admission to some frolic, dance, show or entertainment given by an organization. The prizes offered are in addition to this value received. While the price paid for a ticket is not determined until such 45 ticket is withdrawn from the book, the price never exceeds a certain, fixed maximum amount. Further all chance indicia referred to is intended merely as a special award; something in addition to a ticket of admission; perhaps the privilege of joining some 50 organization without further charge.

Having thus described my invention, what I claim as new and desire to secure by Letters Patent, is:—

60 1. In a sales stimulator book, superimposed leaves each comprising a permanent stub part and a detachable stub part, the latter being provided with a ticket, said detachable stub part bearing a ticket value 65 arranged in staggered relation with respect

to the ticket value of a succeeding stub, the permanent stub parts being arranged to conceal from view the price of undetached tickets.

2. A sales stimulator book comprising a 70 plurality of coupons bound together, each coupon consisting of a stub part bearing upon its face a ticket value and having a ticket attached thereto for detachment with said stub part, and a permanent stub part 75 free of said ticket for concealing the ticket value upon a succeeding ticket stub.

3. A sales stimulator book comprising a 80 plurality of coupons bound together, each coupon consisting of a stub part bearing upon its face a ticket value and having a ticket attached thereto for detachment with said stub part, a permanent stub part free of said ticket for concealing the ticket value 85 upon a succeeding ticket stub, and means for maintaining all stubs concealed during a selling period.

4. A sales stimulator book comprising a 90 plurality of coupons bound together, each coupon consisting of a freely detachable 95 stub portion, of which one part is permanent and of which the other part is connected at one end to the permanent part along a weakened line; bears a ticket value; and has attached thereto a ticket, the permanent 95 part serving to conceal from view the ticket value upon a succeeding stub part.

5. A sales stimulator book comprising a 100 plurality of coupons bound together, each coupon consisting of a stub portion divided upon a diagonal line, of which one part is permanent and of which the other part is connected at one end to the permanent part along a weakened line; bears a ticket value; and has attached thereto a ticket, the permanent 105 part serving to conceal from view the ticket value upon a succeeding stub part.

6. A sales stimulator book comprising a 110 plurality of coupons bound together, each coupon consisting of a stub portion divided upon a diagonal line, alternate stub portions having the line of division arranged in opposed directions, of which one part is permanent and of which the other part is connected at one end to the permanent part 115 along a weakened line; bears a ticket value; and has attached thereto a ticket, the permanent part serving to conceal from view the ticket value upon a succeeding stub part.

7. A sales stimulator book having a cover 120 provided with prize indicia thereon, a plurality of coupons detachably secured with respect to said cover, said coupons each consisting of a ticket bearing chance indicia and a stub part bearing a ticket value, said 125 stub parts being arranged beneath that portion of the cover bearing the prize indicia, and means for maintaining said stubs and said prize indicia concealed during a selling period.

8. A sales stimulator book having a cover provided with prize indicia thereon, a plurality of coupons detachably secured with respect to said cover, said coupons each consisting of a ticket bearing chance indicia and a stub part bearing a ticket value, said stub parts being arranged beneath that portion of the cover bearing the prize indicia, and means including a seal for maintaining 10 the stubs and said prize indicia concealed during a selling period.

9. A sales stimulator book having a cover provided with prize indicia thereon, a plurality of coupons detachably secured with 15 respect to said cover, said coupons each consisting of a ticket bearing chance indicia and a stub part bearing a ticket value, said stub parts being arranged beneath that portion of the cover bearing the prize indicia, 20 a sealing strip arranged over said prize indicia, and a binder secured around said stubs, including said cover and strip, for

concealing from view all but the faces of said tickets when the cover is turned back.

10. A sales stimulator book having a flexible cover provided with prize indicia thereon, a plurality of coupons detachably secured with respect to said cover, said coupons each consisting of a ticket bearing chance indicia and a stub part bearing a 25 ticket value, said stub parts being arranged beneath that portion of the cover bearing the prize indicia, and means securing the latter portion of said cover in abutting relation with the stubs for concealing both the 30 stubs and said prize indicia, but permitting of said cover being folded back along the juncture line of a ticket and its stub.

In testimony whereof I have hereunto signed my name.

JOSEPH L. SCHWARTZ.
